UNITED STATES PATENT OFFICE.

CLAUD E. FULLER, OF NEW YORK, N. Y., ASSIGNOR TO NEW YORK BRICK HANDLING CORPORATION, OF NEW YORK, N. Y., A CORPORATION OF NEW YORK.

CONTAINER.

Application filed October 19, 1927. Serial No. 227,233.

My present invention relates to brick making machinery and more particularly to an improved brick container.

In my copending application, Serial No. 227,231, filed Oct. 19, 1927, I have described and claimed an improved method of manufacturing brick by the soft mud process and in the commercial exploitation of such process, have preferably used improved pieces of apparatus and by means of which the various steps of the improved process may be performed.

One of the most important steps in the practicing of the process is the drying of the brick and I preferably perform this drying operation in an open top dryer, such as is described and claimed in the application Serial No. 227,232, filed Oct. 19, 1927. In connection with the improved open top dryer, I have designed the subject matter of the present invention, which is a container for carrying a predetermined number of layers of pallets on which the green brick are located and which container, when filled, may be placed in an open top dryer with a plurality of containers in each compartment of the dryer, and with the container so constructed and arranged as to form a top for the dryer as the containers are placed therein, and adjacent containers are adapted to be interlocked and have formed therein a practically gas tight joint in order to prevent escape of heated air upward through the tops of the containers rather than pass diagonally through the compartments and out through a predetermined exit. While the container has been designed primarily to handle a plurality of rows of pallets on which are mounted green brick, yet the invention is capable of broader use than that specifically set forth and any cemeric article that requires a preliminary burning or cooking, may be carried by the pallets, or their equivalent, along with or instead of the ordinary green brick.

The object of my invention, therefore, is an improved container.

In the accompanying drawings illustrating a preferred embodiment of my invention,

Fig. 1 is an end elevation;

Fig. 2 is a front elevation;

Fig. 3 is a longitudinal section on the line 3—3 of Fig. 2;

Fig. 4 is a plan view;

Fig. 5 is a section on the line 5—5 of 55 Fig. 4, and

Fig. 6 is a sectional view on the line 6—6 of Fig. 5.

Referring to the drawings, 10 designates a rectangular base, preferably constructed of structural iron and at each corner of such frame are attached risers 11 also of structural iron forms. Secured to the top end of the risers 11 is a rectangular framework 12. The structure thus described, is, therefore, 60 a hollow rectangular framework of greater width than length. On each end of the rectangular framework and secured to the risers 11, are angle irons 13 which form shelves on which may be placed pallets 14 containing 65 a plurality of parallelly arranged green brick 15 or any other articles of commerce that may be desired. Secured to the risers 11 in each side of the device, is a guide 16 for guiding pallets 14 into position between 70 upstanding pairs of risers 11. The top rectangular frame 12 is filled preferably with concrete 17 or with any other suitable heat insulating material, and secured to the top of the rectangular frame 12 are channel 75 members 18 spaced apart from each other and with one end thereof flared outward, as indicated at 19 in Fig. 4. Secured to the top of the channel members 18 and centrally with respect thereof and with respect 80 to the rectangular frame 12 is a plate 20 which may be utilized as a lifting plate by inserting beneath said plate and above the rectangular frame 12, the forked portion of the ordinary lifting fork. At the front and 85 rear faces of the rectangular frame 12 are secured channel members 21 and 22 respectively, the channel member 21 having its open side facing downward, while the channel member 22 has its open side facing upward and in such channel member 22 is placed a layer of sand or other non-combustible granular material 23. The members 21 and 22, together with the granular material 23, affords means for forming a practically gas tight joint between adjacent containers. Assuming a container, such as is shown in Fig. 3, to be thus positioned, a second container may be brought up alongside thereof and the channel member 21 of 90 such second container fitted into the open end of the channel member 22, which will bring one leg of the channel member 21 into

100

105

engagement with the granular member 23 in the channel member 22 of the container shown in Fig. 3.

Referring to Fig. 2, 25 designates side walls of a compartment of an open top dryer and 26 designates the base thereof. The side walls 25 are capped with channel members 27 and against which rests, when the container is in position, the under face of 10 the rectangular frame 12 containing the heat insulating material 17. The container shown in Figs. 1 and 2 has been assumed to have been placed therein by means of a brick lifting fork operated by a traveling crane, and 15 assuming such container, as shown in Figs. 1 and 2, to be loaded with pallets 14 containing the brick 15, it is obvious that the entire weight of the bricks is supported on the top of the walls 25 of the open top dryer 20 by the rectangular frame 12 and, therefore, a practically gas tight joint will be obtained between the tops of the walls 25 and the rectangular frame 12, due to weight alone. As each container is placed in the compartment 25 of the open top dryer formed by the walls 25 and base 26, the channel members 21 and 22 of adjacent containers are interlocked so as to have a gas tight joint formed through the medium of the granular material 23.

It will thus be seen that in an open top dryer, my improved container may be utilized as a combined dryer and closure for the top of the dryer and that the weight of 35 the material is utilized to obtain a gas tight joint between the container and the walls of the dryer compartments while the containers have associated therewith and forming part thereof devices for maintaining a gas 40 tight joint between adjacent containers.

While I have necessarily shown and de-

scribed the preferred embodiment of my invention somewhat in detail, it is to be understood that I may vary the size, shape, and arrangement of parts within wide limits 45 without departing from the spirit of the invention.

Having thus described my invention, what I claim as new is:

1. An improved container for open top 50 dryers comprising a rectangular open framework, a plurality of ledges formed thereon for acting as supports for a plurality of groups of superimposed pallets, and means forming part of the container for making 55 a gas tight joint between the container and an open top dryer.

2. In a container of the kind described, the combination of an open framework, a plurality of ledges therein and forming supports for a plurality of rows of pallets, a rectangular top therefor, and means on said top for forming gas tight joints between adjacent containers.

3. In a container of the kind described, 65 the combination of a rectangular framework, a plurality of ledges therein forming supports for a plurality of rows of pallets, a top therefor formed of a layer of heat insulating material, and means associated with 70 such top for forming a gas tight joint between adjacent containers.

4. In a container of the kind described, the combination of a frame, ledges therein forming supports for a plurality of pallets, 75 a top therefor of heat insulating material, and means secured to the top for permitting attachment thereto of a lifting device.

In testimony whereof, I have signed my name to this specification.

CLAUD E. FULLER.
